PETER COOPER HEWITT, OF RINGWOOD MANOR, NEW JERSEY, ASSIGNOR TO COOPER HEWITT ELECTRIC COMPANY, OF HOBOKEN, NEW JERSEY, A CORPORATION OF NEW JERSEY.

METHOD OF AND APPARATUS FOR TRANSLATING ELECTRICAL VARIATIONS.

1,262,491.

Specification of Letters Patent.

Patented Apr. 9, 1918.

Original application filed March 30, 1907, Serial No. 365,597. Divided and this application filed May 15, 1915. Serial No. 28,435.

To all whom it may concern:

Be it known that I, PETER COOPER HEWITT, a citizen of the United States, and resident of Ringwood Manor, in the county 5 of Passaic and State of New Jersey, have invented certain new and useful Improvements in Methods of and Apparatus for Translating Electrical Variations, of which the following is a specification.

10 My present invention involves the discovery of certain phenomena developed by the flow of electric current through a gas or vapor, and it particularly concerns the utilization of such phenomena in connection 15 with electrical variations of all kinds and for various purposes.

It is useful in connection with very rapid and very feeble electrical variations, and is particularly adapted to translate variations 20 of potential. When used for detecting the oscillations in the receiving circuit of a space telegraph or telephone system, the results demonstrate extreme sensitiveness, reliability and durability.

25 My invention contemplates the employment of one or more special or auxiliary terminals, or electrodes, in operative relation to a gas or vapor carrying current, said current being supplied to the gas independently of such auxiliary terminal or terminals.

The geometrical characteristics of the conducting vapor may be determined by the size, shape, etc., of a containing vessel and by the size and position of electrodes therein.

30 The electrical characteristics of the gas or vapor are dependent upon the geometrical characteristics, upon the kind and purity of the gas or vapor, upon the nature and material of the electrodes, and upon the density

35 of the vapor. The density of the vapor depends upon the temperature and pressure, and the initial density of a given vapor in a hermetically sealed container, may be varied through changes of terminal temperature.

40 Normal or initial internal temperature is dependent upon the temperature of the surroundings. Changes of temperature during operation are dependent upon the ratio of heat generation to heat radiation. The internal heat generation is dependent upon the above mentioned electrical

characteristics and upon the amount of current flowing in the vapor device. The heat radiation is dependent upon the heat radiating area and the temperature of the surroundings. Hence, in the operation of a vapor device having given geometrical and electrical characteristics of construction, the density of the vapor is controllable by regulating current flow, heat radiating area, and 55 temperature of the surroundings.

The reactions attending passage of current in a conducting gas or vapor may be subdivided into three definite classes; (1) reactions at and near the positive electrode 60 or anode; (2) reactions in the gas or vapor itself; and (3) reactions at and adjacent the negative electrode, or cathode, including reactions at the junction of the negative dark space with the vapor carrying current 65 from the main positive electrode.

The separate phenomena of which the reactions at the positive electrode or anode are made up, are numerous, and are chiefly modified by the position, size, and physical 70 state of the anode; and by the purity, density, and kind of gas; and also by current density in the gas. Certain of them are sensitive to magnetic action. One of the visible reactions of the positive electrode 75 or anode, is a luminous ball or bush which is very sensitive to magnetic action and which tends to be a source of variation. At low densities it is very sensitive to magnetic action.

80 The reactions in the conducting vapor itself and modifications thereof, independent of the reactions near the electrodes, have been broadly stated by me. They may be modified by a magnet, especially at low 85 densities. The reactions of the vapor column are normally stable, and for purposes of this invention, its length, the kind of gas, the gas density, and the current density 90 are chief modifying factors to be considered 95 and controlled.

The phenomena at the negative electrode are numerous, and include two distinct classes; one class being those found at the negative electrode when it is in its primary 10 condition, before it has been changed to what has been termed by me its "low resist-

ance" or "broken down" state, and another class being those which exist after the negative electrode has attained the low resistance state. It is characteristic of the first 5 mentioned class that on subjecting the negative electrode in the primary condition, to sufficient electrical stress, a certain point is reached where a leakage current may be observed under certain conditions. A modified 10 leakage current flowing under low stress is manifest when said electrode is present in a current carrying vapor having sufficient current density. The opposition or apparent resistance to this leakage current, 15 is modified by the surface area of the electrode, and by the current density in the vapor adjacent thereto, and it varies in ways peculiar to itself with the nature, purity and the density of the vapor, 20 and with the nature and condition of the electrode. It varies with the temperature of the negative electrode, and if this temperature be increased to incandescence, this 25 resistance then reaches or comes near its minimum limit. After the last state of resistance in the primary condition has been reached, if the temperature of the electrode be increased to such a point as to bring about a physical or chemical change of 30 state of the electrode, while current, with sufficient backing, is passing into said electrode, the reactions will change to those of the second class; namely, those attendant upon the broken down state of resistance, 35 and the reactions of the negative electrode will then be measured by a less drop in potential. It is often desirable that the drop over the device should be as small as possible and in such case this latter state should 40 serve best. This broken down state of the negative electrode may be attained by various expedients now well known in the art.

Accompanying this change are the visible phenomena of the negative flame to which 45 I have before called attention. The visible phenomena consist of a bright spot on the negative electrode with a flame apparently hovering over this spot. The peculiar characteristic of this flame is that it tends to 50 lie in and along the magnetic lines of force, rather than to be twisted or distorted by them, as is usual to current passing. It tends normally to project itself perpendicularly from the surface of the electrode. A 55 magnet may be used to modify or adjust the conditions at the negative electrode. The bright spot tends to locate itself at a meniscus of an irregularity on an electrode.

The flame itself is surrounded by a dark 60 space and when the flame is in normal position in a right line with the vapor column, the top of the flame usually marks the boundary of the dark space where it joins the luminous positive column of conducting 65 vapor coming from the positive electrode.

The flame is very sensitive to electrical variations, and such variations may be observed when looking at it. Its reactions may also be varied by a magnetic field and its reactions may be made usable in this 70 way. When the positive electrode is arranged at comparatively short distances from the negative electrode as, for instance, when located within the dark space, there may be no luminous positive column, and 75 the reactions at the positive are modified at certain distances from the cathode and may be rendered practically unnoticeable. The positive bush reaction may be practically eliminated by these means. The length 80 of the vapor column is decreased so that the total voltage drop across the device is decreased, and the drop due to the positive bush may be seriously modified if not altogether eliminated. Many of the above 85 described reactions are modified by rapid electrical variations and are useful in connection with them.

In the practice of my invention I expose 90 within the vapor device, supplied with current through main electrodes, a separate terminal or two or more terminals operatively associated with a telephone or other indicating instrument and with a source of variation to be detected.

The relative positions of such terminal and of the main electrodes are of considerable importance because, other things being equal, the effects of the reactions at an auxiliary terminal of this type, seem to vary with the 100 charge in the body of the vapor, particularly in the region immediately adjacent such auxiliary terminal. The current density in the vapor varies with the total amount of current flow between the main electrodes 105 and also with the relative position or location of the auxiliary terminal with reference to the main electrodes and the current path between said electrodes. Hence, for given conditions, the proper current density 110 or charge of the vapor adjacent an auxiliary terminal, may be attained by adjusting or arranging the auxiliary terminal nearer to or farther from the main electrodes and the path between them, or, where the auxiliary 115 terminal is already fixed in a suitable position, by increasing or decreasing the amount of current flowing between the main electrodes. The latter expedient will usually have the effect of changing the density and distribution of the current in the vapor and may be availed of to a certain extent.

The relation of the size of the auxiliary terminal to the current or charge carried 125 by the vapor is important, and as a rough rule, the size should be decreased when the charge in the vapor is increased to obtain approximately the similar effects. And further, if it is desired to vary the effect, increase of the area of the auxiliary termi- 130

nal will have an effect somewhat analogous to increase of charge or current density in the body of vapor adjacent thereto.

By increasing the main current when receiving even faint signals, the volume of the signal may be amplified in many arrangements of this device, and this may be continued up to the point where they begin to be obscured by other variations developed.

Whatever type of device be employed for maintaining the supply of current in the vapor, such supply should be independent of the auxiliary electrode used for detecting purposes. An auxiliary electrode, because of its position or electrical connections, may have a tendency to be a positive or a negative electrode with reference to the vapor, or, being maintained at a neutral point, as by a source of counter-electromotive force, or by a condenser which may be used as such, it may under certain conditions tend to act as either, or alternately, as both. For some purposes it is preferable that it be arranged so as normally to have no current flowing either from or to it, except such currents as are the result of the action of the electrical variations to be detected, and in case it is desired that the device should have a rectifying action, the auxiliary electrode should tend to oppose a prohibitive barrier to the passage of current from the vapor into it. This action seems to be more complete when the current flow in the vapor adjacent to it is at or near a minimum and its surface area is not too great.

The reactions at the positive electrode are normally in an unstable state and give rise to rapid electric variations, which when heard in a telephone are rumbling, rattling, cracking sounds, and may, under certain conditions, produce clear musical notes. One means of rendering the reactions at the main positive electrode substantially stable, is to bring such main positive electrode in close proximity to the main negative electrode. In such case, the visible phenomena at the main positive electrode and the voltage drop, are modified and largely suppressed, and the attendant reactions may be so rendered practically noiseless to a telephone at an auxiliary electrode.

The size of the positive electrode is important with reference to the heating effect on it and also with respect to the bush reaction, and for most purposes it should be of sufficient area to pass the desired maximum current without becoming unduly overheated but it should not be too large on account of the bush reaction. It may be designed to be highly heated and its temperature may be made to affect the reactions at the negative electrode, as well as its own.

The vapor column, considered by itself, rarely presents any sources of irregular or detrimental electrical variation. It is desir-

able to use means to maintain the current in the vapor normally constant and uniform in quantity and in distribution.

The internal variations may be modified by a magnetic field external to the device, the exact position and distance of the magnet suitable for given conditions being usually determined by a few trials. The magnetic field thus employed may be made to vary the internal resistance of reactions, and will often increase the sensitiveness of the device. The desired direction and distribution of the lines of force of the field may be established by proper design and location of a single magnet, or a plurality of magnets may be used to establish a resultant field. With a ring positive electrode, it is usually desirable to have the lines of force somewhere about 45 degrees from the normal direction of the negative electrode flame and with a disk positive electrode approximately parallel with such direction.

In all forms shown herein the conducting gas or vapor is inclosed in a suitable container preferably having three or more electrodes. The electrical reactions at the various electrodes and in the conducting medium may be thus caused and controlled as desired, to enable the development of suitable reactions within the medium itself for the desired purposes and to make possible the modification and control of the reactions. The temperature and density of the gas or vapor may be controlled in any desired way, as by determining the area and disposition of the outer radiating surfaces of the container or by the use of suitable expedients for increasing or decreasing the heat absorbing or heat imparting power of the surroundings.

In all of the forms shown herein, the conducting medium is referred to as a gas or vapor medium contained between electrodes in a hermetically sealed vessel, but similar circuit connections may be made serviceable in connection with other mediums having similar reactions. A pure gas is preferable, however, since it tends to insure uniformity of the reactions and I prefer to use a monatomic gas such as is afforded by mercury or mercury vapor in a hermetically sealed vessel or container. The container and any solid electrodes therein, are preferably of such material as not to yield gases under the conditions of operation. The methods of cleansing and evacuating such devices by washing with mercury vapor and exhausting the same while subjected to the action of heat and of the electric current, are now well known in the art.

A starting band of the type well known in the art may be applied at a main negative electrode, as at C², or an auxiliary electrode, as at C³, and may be used according to the practices well known in the art, or may be

utilized as a means of operatively applying to the device, the variations to be translated or detected.

While my above described invention contemplates the utilization of reactions developed by current flow in a circuit which includes a gas or vapor as one of the conducting media, it will be understood that the special or auxiliary terminal and the circuit arrangements may be employed in connection with other conducting media carrying current supplied to the medium independently of the auxiliary terminal. In general the circuits whose reactions are to be utilized, should include differently conducting media affording variable electrical, reactions of various classes, such as transition resistances, etc. I prefer a true conductor of the first class, such as ordinary conducting metals, and also a conductor of another class of conductivity as, for instance, one which is adapted to pass current after the manner of electrolytes or conducting fluids such as gases or vapors. A suitable source of electromotive force should be employed to maintain normal current flow in the circuit of the fluid medium, said current flow being preferably of relatively large quantity and low voltage. The indicator circuit should be lateral or branch or parallel circuit including a part only of the fluid medium of said first mentioned circuit.

The source of variations to be translated may be a circuit of either forced variations or oscillatory variations and may be an open circuit, connected to ground or a capacity, or not, as desired. A closed circuit of either forced variations or oscillatory variations may be applied to advantage or any of the arrangements shown in each and all of the figures of the drawings by connecting the two sides of such closed circuit in the same way that the aerials S and ground G respectively are connected, or in any other desired way, all as will be well understood by those skilled in the art.

I have specifically shown and described herein only a few of the typical and desirable ways of arranging the serial, indicating and direct current supply circuits. From these it will be evident to one skilled in the art that my vapor device is so sensitive that the variations to be detected or translated can hardly be applied to the same in such manner as not to produce some effect on the internal reactions and that those reactions will produce more or less pronounced sensible effects in the indicator whenever the latter is applied to the vapor device in such manner that impulses, direct currents, or displacement currents may flow therethrough in response to potential variations. The instrument should be designed or located so as not to be injured by the amperage of such current flow, and, in general,

it is preferable to arrange the indicator and variation circuits in such manner that the variations to be detected may pass to the vapor device without being impeded or choked out by the indicator.

This is accomplished by bringing the aerial receiving conductor or other desired source of variations, into operative relation to the vapor device by connecting it directly to one or more of the auxiliary electrodes, 70 or by connecting it to a capacity area arranged in electrostatic relation to an auxiliary electrode or to the vapor path between it and the main electrodes. This may be done by employing a capacity area in the 75 form of a metal or tinfoil plate a foot or so in diameter, which is preferably located very close to the container, but it may be located some inches or even some feet away. Such sheet or plate is illustrated in my application, Serial No. 365,597, filed March 30th, 1907, of which this application is a division; and broad claims for the device in broad combination with means for electrostatic application of received variations, 80 as based on such embodiment of my invention, are contained in said application. In this application I claim the method and also certain special devices, combinations and elements not specifically claimed in said 85 prior application, as for instance the capacity area consisting of a conducting band encircling the device adjacent an auxiliary electrode, in a manner analogous to the so-called "starting band" which is well-known 90 in the art as a means for electrostatically affecting the main negative electrode of mercury vapor devices for starting flow of main current between the main electrodes.

In the accompanying drawing the container is shown in vertical section with the circuit connections thereof diagrammatically indicated, the figures correspond respectively to Figures 2, 4, 12, 15, 21 and 22 of my said prior application. The means 100 for applying variations is shown as electrostatically associated with the other elements of the apparatus, but it will be obvious that so far as concerns certain aspects of the inventions, the variations may be conductively applied.

Fig. 1 is a view showing the electrostatic band encircling an auxiliary electrode located between widely separated main electrodes, the negative electrode being provided with means for rendering more stable the reactions thereat.

Fig. 2 shows the auxiliary electrode at the top of the container and the positive electrode arranged close to the negative electrode in such manner as to render more stable the reactions at the positive electrode.

Fig. 3 shows an arrangement in which there are two ring electrodes adjacent to the negative electrode, one of them used as 105

a main positive electrode and the other used as an auxiliary electrode in connection with a second auxiliary electrode on the top of the container.

5 Fig. 4 shows a container substantially the same as in Fig. 2, associated with a typical indicator circuit.

Fig. 5 shows a similar container but having the auxiliary electrode in the form of 10 a plate and associated with another typical receiving circuit. In this form the main positive electrode is adapted to heat a projection from the negative electrode.

Fig. 6 is a detailed view showing a modified arrangement of main electrodes which 15 may be used in the container of the preceding figures.

Fig. 7 illustrates a vapor device associated with a magnetic field and arranged 20 in shunt to the condenser of a close tuned or resonant circuit, inductively associated with a primary source of variations.

In various of the figures of the drawings, 25 electrodes of thin material having various outlines, are shown as viewed from a point above the planes of said electrodes, in order to show the structure more clearly. While any one of more of these electrodes may be arranged at various, similar or different 30 angles, it is to be understood that these electrodes may be and preferably are arranged with their flat surfaces lying in planes at right angles to the axis of the vapor device. In either case the device is preferably normally operated in a vertical position, but 35 may be and frequently is operated in a tilted position as desired, in order to vary internal conditions for particular purposes or conditions.

40 In the various figures of the drawings, the specific devices embodying my invention comprise main positive and negative electrodes, one or more auxiliary electrodes, and a suitable container. The main electrodes 45 are supplied with current from a suitable source, preferably a direct current source, indicated in the drawings as a storage battery. This supply circuit is provided with suitable regulating devices, including preferably an adjustable ohmic resistance and 50 an inductance which is also preferably adjustable. The ohmic resistance and the inductance may be more or less embodied in the same device, but are preferably separate. Suitable receiving and indicating 55 circuits are operatively associated with the auxiliary electrode.

Like parts have been indicated by like reference characters on the various figures 60 wherever this is possible without liability to cause confusion.

Referring more particularly to Fig. 1, the positive electrode 1 may be any known or desired material suitable for the purpose, 65 such as iron, platinum, carbon, or other con-

ducting material. The particular cup shaped electrode shown in this and other figures, is preferably of the same material, size and shape as the positive electrode now in general use in the Cooper-Hewitt lamps. 70

The negative electrode 2 consists of a body of conducting liquid preferably of mercury. The auxiliary electrode 3 is preferably a solid conductor of iron, platinum, carbon, or other suitable material. The container 4 is preferably of glass, preferably hermetically sealed and preferably having a high vacuum when cold. It may be of any suitable or desired size, and may be conveniently made about 2-1/2 to 3 inches 80 in diameter and about 5 or more inches in height. A device of such diameter and 7 inches in height will have a current carrying capacity through the main electrodes up to 4 or 5 amperes at pressures of, say, 7 to 85 25 volts, and will have ample heat radiating area.

The source of current supply is shown at 8, an adjustable resistance at 9, and an adjustable inductance at 10. The supply circuit is thus capable of regulation for purposes of controlling the amperage through the lamp and for steadyng the same to normally uniform values. 90

The auxiliary terminal 3 is sensitive to 95 the electrical variations to be detected and these are operatively applied to the device from any suitable source of variation, as, for instance, a receiving wire S of a space telegraph or telephone system connected directly to the auxiliary terminal or brought in proximity to the device as by connecting it to the bend or collar C³ arranged adjacent thereto. It will be understood that the variations to be utilized, may be from other 100 sources and may be of comparatively low frequency and greater amperage. Where the variations to be utilized are feeble or rapid, it is desirable to connect the supply wire S in electrostatic relation to the auxiliary electrode 3 so that there shall be little capacity or impedance in the supply circuit leading to the auxiliary electrode. The detecting circuit is preferably arranged to have a suitable value of impedance, that furnished by a telephone receiver serves well, and a telephone having a resistance of 105 500 to 2000 ohms is frequently found suitable for the purpose of wireless telegraphy. In case the impedance is the primary of a 110 transformer, the inductance and resistance may be selected to suit, as desired. The receiver or indicator circuit R connected at one end to an auxiliary electrode, may be connected at the other end to a capacity, or 115 to the main positive or negative electrode or in a multiplicity of ways hereafter more fully referred to. In Fig. 1 it is shown connected to a capacity area C³, which for space signaling purposes need not be very 120

125 130

large. A ground connection C is sometimes desirable, but not always necessary, and may be made by connection from a main electrode as in Fig. 3, as desired.

5 In a vapor device of the kind shown in Fig. 1, any internally originated disturbing variations at the main electrodes, due to the passage of the battery current, will be manifest at the auxiliary electrode and tend 10 to obscure its action when minute variations are to be detected. Hence in Fig. 1 I show the device provided with one of the various possible means for lessening the internally originated disturbing variations, by 15 rendering the reactions at the main negative electrode more stable. This result is accomplished by arranging a projection 12 extending above the surface of the mercury 2 and wetted thereby, after the manner here- 20 inbefore referred to. A platinum wire projecting a short distance and having a diameter of .045 inch, serves well for this purpose, for currents of from 1-1/4 to 2-1/2 amperes or even more.

25 Fig. 2 represents a similar vapor device having the reactions at the negative electrode rendered stable in the manner just described, and embodying also a means for rendering stable the reactions at the positive electrode. In this form the positive electrode 11 is brought into close proximity to the negative electrode and arranged in the form of a ring symmetrically surrounding the projection 12 of the negative electrode, above and preferably parallel with the surface of the mercury 2 and preferably slightly above said projection. If the ring is used in the form of a flat disk of iron 30 1-1/8 inches in external diameter and 1/4 35 inch or less in internal diameter, it will pass 2-1/2 to 3 amperes of current without 40 becoming unduly heated.

The internal diameter of the ring should not be too great with respect to its distance 45 from the projection 12, for otherwise there may be a tendency to unstable reactions giving rise to disturbing fluctuations. Ring electrodes of the above specified sizes, however, carrying currents as described, are very 50 suitable for the purpose, but this electrode may be varied in size and shape and may be a disk or other shape.

A convenient method of determining or 55 adjusting the distance of such a positive electrode from the surface of the mercury consists in providing the container with a pocket 15 adapted to contain an extra supply of mercury 16. In such a device the desired amount of mercury may be poured 60 off from the negative electrode into the pocket, or vice versa.

In this form of device the starting may be conveniently effected by shaking the device so that the mercury of the negative electrode

momentarily comes in contact with the positive electrode, thereby making and breaking a bridge.

With the above described arrangements, the visible phenomena at the main positive electrode and its resistance are modified and largely suppressed and the attendant disturbing reactions are made practically unnoticeable so far as concerns their effects at the auxiliary electrode and in the indicator connected thereto. The device may 75 be operated at a lower potential than that of Fig. 1 and it has a much greater current capacity, the latter being limited, in practice, mainly by the size and fusibility of the positive electrode.

The heating effect at the positive electrode is less as the surface of the positive electrode is increased, and this arrangement may be used to carry current up to 5 amperes at a voltage of 7 to 10 or 12 volts, depending 85 upon the characteristics of the particular device. The operation of this form of device, under varying conditions, seems to vary with the position of the positive electrode with respect to the negative electrode, particularly for positions varying from barely 90 out of contact with the surface of the mercury to, say, 5/8 inch or more from the surface of the mercury.

In this case also, the wireless or other 95 source of variations is connected directly to the electrostatic band adjacent the auxiliary terminal. In this figure, as also in Figs. 3, 4 and 7, the upper cup shaped terminal is used as an auxiliary electrode but, as in the 100 case of Fig. 1, the electrostatic band or strip is located so as to inclose the active part of the electrode in an encircling electrostatic field.

In Fig. 3 there are two ring electrodes 31, 105 32 located one above the other. There is also a cup shaped electrode 13 at the top. Either one of the ring electrodes or the cup shaped electrode may be used as the main positive or as auxiliary electrode or electrodes.

When the upper ring electrode 32, is not used as a main electrode, it appears to serve some useful purpose with reference to the reactions occurring at the main electrodes. 110 One apparent effect is that it tends to prevent adherent deposits on the walls of the container, which otherwise frequently occur and which appear to be caused by exfoliations from the point 12 of the negative electrode.

In this figure the indicator connection is from the upper cup shaped auxiliary electrode 13, to the lower ring electrode 31, which is located in the dark space between, 125 and adjacent to the main electrode, the upper ring electrode 32 being used as a main positive electrode. The indicator is

located in a circuit connected between this auxiliary electrode located in the dark space, and a remote auxiliary electrode 13.

In Fig. 4 the container, main positive and negative electrodes, auxiliary electrodes, and the electrostatic band for applying the variations are all substantially as in Fig. 2. In Fig. 4, however, the indicating circuit is from the auxiliary cup shaped electrode 13 at the top of the container, through the indicating device to the negative electrode 2, as shown. The indicator R may be an electromagnetic telephone receiver having sufficient impedance for the particular purpose in view, for instance, 100 to 2000 ohms resistance.

In Fig. 4 the electromotive force across the indicator circuit from the auxiliary terminal to the main negative electrode is more or less counter-balanced, or if desired, overbalanced by the potentiometer 18 shown. The latter may be adjusted to cause slight current flow to or from the auxiliary electrode, and this device may be used in connection with the other devices and circuits shown herein.

Fig. 6 shows a form of device wherein there may be special heating action of the positive electrode 11^b on the negative electrode when the positive electrode is so designed with respect to the current flowing therethrough as to be highly heated. To this end the positive electrode is made small, so as to become heated by the passage of current from it, and is concentrically arranged around a projection 12^a from the negative electrode, which it tends to heat, this projection tending to render stable the negative electrode reactions at its base. Such a positive electrode being constructed of platinum wire .057 inches in diameter and wound in a helix, having an inside diameter of 1/4 inch and being of two turns, will become heated with 1 ampere passing, and will work with 1-1/2 amperes, the bottom of the helix being substantially 1/8 inch from the level of the mercury.

In Fig. 5 the vapor device is shown with connections to a receiving circuit which may be useful with other forms of the device. The receiving conductor S is shown tuned as at 47 to a quarter wave length and the lateral conductor 45 leading to the electrode 13^c of the vapor device is also tuned as at 46 to the same frequency. The ground connection G may be adjustably connected to the coil 46, 47, 46, as at 48, and when such ground is used the circuit G, 48, 47, S will be the electrical equivalent of the circuit G, 48, 46, 45, 13^c, so that there will be a crest of potential at 13^c.

In Fig. 7 the vapor device is shown as connected through a lateral conductor 54 with a closed tuned or resonant circuit, pref-

erably tuned to the frequency of the received energy to be detected by means of a suitable adjustable inductance 51 and an adjustable condenser 52. This closed tuned circuit is associated by means of a transformer 53 with a receiving wire S, and the parts may be all designed and operated in accordance with any of the principles well known in the art. The lateral conductor is shown adjusted as at 55 to the quarter wave length of the received energy so that there will be a resonant rise of potential at C³.

Referring more particularly to the arrangement of Fig. 5, if the auxiliary electrode 13^c be a circular plate 1-1/4 inches in diameter and its distance from the mercury negative electrode 2 be five inches and the main positive electrode be a ring of iron 1-1/8 inches outside diameter having a hole in the center 1/4 to 5/16 inch in diameter and if it be situated 3/8 of an inch from the surface of the mercury electrode, the container vessel being substantially from 2-1/2 to 3 inches in diameter, and properly exhausted, said vapor device will respond to extremely faint variations. Its sensitiveness may be increased by approaching an ordinary permanent magnet M somewhat in the manner shown in Fig. 7, the distance varying from close proximity to the device to 18 inches or so from it.

A second magnet applied as shown in Fig. 7 may have a beneficial effect in tending to produce a resultant magnetic field wherein the lines of force lying in the path above 11 and 12 are at an angle of approximately 45 degrees from the normal vertical position of the negative electrode flame.

The various conditions of electrode size and location, main current flow, etc., may be so adjusted by trial as to cause a whistling sound or a regular note in the telephone when the magnet is at a suitable distance from the container. By then adjusting one of the variables, preferably the magnet, the device may be put in a critical or unstable condition, where faint signals may be indicated by perceptible changes in the quality, pitch, or intensity of such sound. In some cases the device may be put in a condition where there is little or no perceptible note audible and yet the balance is so delicate that the faintest disturbance, will precipitate the sound of the note, thus giving a strong signal where otherwise the effect might be nearly or quite inaudible.

The circular auxiliary electrode 13^c is shown in Fig. 5 as flattened and arranged in a transverse plane with the flat surface approximately equidistant from the path between the main electrodes, so that almost all of the surface of the electrode exposed to the vapor lies in an approximately equi-potential region of suitable current density.

This arrangement has certain advantages where it is desired to use a fine adjustment of counter electromotive force of a potentiometer to secure the most sensitive condition for feeble signals. One reason for this is that if the auxiliary electrode is formed or arranged so that the exposed surface thereof extends through regions at materially different distances from the path between the main electrodes, different parts of such exposed surface may lie in regions of materially different current density. While this latter condition may not be objectionable for many purposes, it is sometimes found to be unsatisfactory for the finest work in connection with the faintest signals.

One probable reason for this is that the condition of most extreme sensitiveness of the auxiliary electrode seems to depend upon getting an extremely fine balance of the counter electromotive force of the potentiometer against the electrical pressure at the surface of the auxiliary electrode. The latter pressure has for one important determining factor the current density in the portion of the vapor in contact with the electrode, and it seems to be a fact that if the auxiliary electrode is so formed or arranged that there are materially different current densities in the vapor adjacent different portions of its surface, the counter electromotive force of the potentiometer when set to a proper value for the current density adjacent one portion of the exposed surface, will be either too great or too small for other portions where the adjacent current density is of different value. On the other hand, if all portions of the exposed electrode surface are acted upon by vapor or substantially the same current density, the counter electromotive force may be very accurately adjusted to that current density, and such adjustment being perfect for one portion of the electrode is perfect for any other portion of the electrode.

Another reason may be that a uniform density or current flow into and out of a considerable area of the electrode may be desirable. This result should be accomplished by the above arrangement of the auxiliary electrode, because by it the lengths and resistance of the vapor path from different portions of the surface of the electrode, will be substantially equal.

My experiments show that other things being equal, the perforated plate or ring positive electrode of Fig. 7 seems to give smoother effects more directly proportional to the received variations, whereas an imperforated disk seems to give more distorted or disproportionately amplified indications. This quality of the disk or imperforate plate seems to preserve the value of the amplified variations more accurately

and to be better adapted to translate telephone variations.

The device described herein may be designed so as to be used for the purpose of receiving varying impulses of any frequency or strength and making them serviceable on direct current devices. It is also adapted for telephonic purposes, particularly for wireless telephony.

The asymmetric resistance characteristics of the vapor device when constructed and operated as herein explained, may be made to persist for the highest frequencies as well as for the lowest voltages, and these characteristics may be relied upon for the rectification or asymmetric translation of variations of an extremely small fraction of a volt and of the highest frequency, thereby rendering possible the use of a direct current indicating instrument.

I have found it desirable in order to fully utilize the asymmetric resistance characteristics of the device to so arrange the auxiliary electrode that it will act as an approximately no resistance positive electrode and as a substantially prohibitive negative electrode with respect to oscillations of the strength which it is desired to translate or detect by such device.

This result may be achieved in connection with any of the typical circuits and devices shown herein. Referring for convenience to Fig. 5, the electrode 13^c should be located at such distance from the main electrodes 11, 12 that the current flow therefrom and the current density of the vapor adjacent thereto is near the point where normal internal variations begin to cause disturbing indications in the instrument R. In a particular case this distance might be somewhere between 4 and 7 inches or, say, about 5 inches. The distance should be and in the case mentioned usually will be, such that the current density in the vapor adjacent the auxiliary electrode will not be sufficient to neutralize the opposition or reluctance of such electrode to act as a negative electrode with respect to impulses of the strength which it is desired to rectify. Under such conditions

the flow of current from the auxiliary electrode into the vapor will be measured by a normal voltage drop at the auxiliary electrode which may be some 1, 2, 3, or more volts, according to the conditions. The application of electromagnets after the manner described in connection with Fig. 7 may serve to reduce this voltage drop to a fraction of a volt, say, for instance, to 7/10 volt or less. If now the potentiometer 18 be applied as a source of counter electromotive force, this drop may be counterbalanced by adjusting the potentiometer to a pressure of, say, 7/10 volt in the opposite direction. It is a peculiarity of such device, however, that in order to suppress the effects of inter-

nally originated disturbances in the telephone R, the counter electromotive force should be slightly greater than the original drop, or say somewhere about 75/100 volt, 5 where the drop was found to be 7/10 volt. By still further experimental refinement of adjustment of this counter electromotive force, the voltage drop at the auxiliary electrode may be reduced practically to a zero, 10 so that half waves or impulses of the smallest fraction of a volt, say, for instance, 1/10 volt to 1/100 volt, or less, will pass freely and practically unimpeded into the vapor, whereas the half waves or impulses tending 15 to run in the opposite direction will be blocked and prevented from passing from the gas into the electrode 13°, so that the effects of the variations are observable in a direct current instrument. The adjustable 20 potentiometer thus arranged, is an accurate means for attaining at the electrode 13°, the conditions which will best serve the purpose of detecting alternating currents by a direct current instrument and yet not give rise to 25 undue internally originated disturbances which might tend to mask the effects in the indicator R.

While I have last above described an arrangement of my device which is particularly efficient for rectifying, it will be understood that the device is so remarkably sensitive in such a variety of ways that it will act as a very good detector of feeble variations such as are characteristic of the receiving wires of ordinary commercial wireless telegraph systems, even when the adjustments are such that the asymmetric action is at a minimum.

With reference to magnets, it will be understood that the position and number of the magnetic lines and their action with respect to the negative electrode flame and other phenomena, may be varied as desired, to suit the conditions.

45 I claim:

1. An apparatus for translating electrical variations comprising a translating device and a connection therefrom through an electrode to a body of conducting gas or 40 vapor, adapted to be maintained in a low resistance conducting condition in combination with means for continuously maintaining current in said vapor independently of said electrode, and a conducting band for 45 electrostatically applying variations to said apparatus, substantially as described.

2. An apparatus for translating electrical variations comprising a translating device and a connection therefrom through a true 50 conductor of the first class to a conducting gas or vapor maintained in the low resistance conducting condition in combination with means for continuously maintaining current in the gas or vapor independently 55 of said connection through said true con-

ductor, and a conducting band for electrostatically applying variations to said apparatus, substantially as described.

3. An apparatus for translating electrical variations comprising a translating device 70 and a connection therefrom through an electrode to a body of conducting gas or vapor and means for limiting or preventing normal direct current flow through said electrode, in combination with means for 75 continuously maintaining current in said vapor independently of said electrode, and a circular band for operatively applying variations to said apparatus, substantially as described. 80

4. An apparatus for translating electrical variations comprising indicator, variation and main current supply connections, in combination with an evacuated container provided with electrodes for maintaining 85 normal current flow therein, the positive electrode extending into the dark space adjacent to the negative electrode, together with an encircling band variably charged through said variation connection. 89

5. An apparatus for translating electrical variations comprising indicator, variation and main current supply connections, in combination with a gas or vapor tube provided with electrodes for maintaining normal current flow therein, the positive electrode extending into the dark space adjacent to the negative electrode, and one of them being of vaporizable material; together with an encircling band variably charged through 95 said variation connection. 100

6. An apparatus for translating electrical variations comprising indicator, variation and main current supply connections, in combination with a gas or vapor tube, provided with electrodes for maintaining normal current flow therein, the positive electrode extending into the dark space adjacent to the negative electrode, the negative electrode being of vaporizable material and 105 provided with means for anchoring the negative electrode flame; together with an encircling band variably charged through said variation connection. 110

7. An apparatus for translating electrical 115 variations, comprising an evacuated container, coöperating electrodes, circuit connections therefor, and an indicator, operatively associated therewith, in combination with a capacity area consisting of an encircling band in inductive relation to said container, and a source of electrical variations connected to said capacity area, for the purpose described. 120

8. An apparatus for detecting feeble electrical variations comprising a hermetically sealed container having a high vacuum when cold and provided with main electrodes, an auxiliary terminal, and a circuit therefrom through an indicator, in combination 125 130

tion with a capacity area consisting of an encircling band in operative relation to said container, and a main circuit for maintaining current flow through said main electrodes of sufficient quantity to maintain the main negative electrode in the broken down state, substantially as described.

9. An apparatus for detecting feeble electrical variations comprising a hermetically sealed container having a high vacuum when cold and provided with main electrodes and means for rendering stable the normal internal reactions, an auxiliary terminal, and a circuit therefrom through an indicator, in combination with a capacity area consisting of an encircling band in inductive relation to said container, and a main circuit for maintaining current flow through said main electrodes of sufficient quantity to maintain the main negative electrode in the broken down state, substantially as described.

10. An apparatus for detecting feeble electrical variations comprising a hermetically sealed container having a high vacuum when cold and provided with main electrodes, an auxiliary terminal, and a circuit therefrom through an indicator, in combination with a capacity area consisting of a band mounted upon said container, adjacent said auxiliary electrode, and a main circuit for maintaining current flow through said main electrodes independently of said auxiliary terminal.

11. The method of utilizing the reactions at an electrode in a gas or vapor device supplied with currents independently of said electrode, which method consists in correlating the location of the exposed surface of the electrode and the distribution of the independently supplied current so as to present an approximately prohibitive negative electrode resistance to passage of current from the vapor into said third elec-

trode and an approximately minimum resistance to passage of currents in the opposite direction, and applying electrical variations by electrostatic induction in the region of said electrode and the adjacent vapor, substantially as described.

12. The method of utilizing the reactions at an electrode in a gas or vapor device supplied with currents independently of said electrode, which method consists in correlating the location of the exposed surface of the electrode, the distribution of the independently supplied current and the electromotive force of the circuit of said electrode so as to present an approximately prohibitive negative electrode resistance to passage of current from the vapor into said third electrode and an approximately minimum resistance to passage of currents in the opposite direction, and applying electrical variations by electrostatic induction in the region of said electrode and the adjacent vapor, substantially as described.

13. The method of utilizing the reactions at an electrode in a vacuum device containing a monatomic gas or vapor supplied with currents independently of said electrode, which method consists in correlating the location of the exposed surface of the electrode and the distribution of the independently supplied current so as to have its reactions at or near the point where its opposition to the passage of negative current approaches a maximum, and applying electrical variations by electrostatic induction in the region of said electrode and the adjacent vapor, substantially as described.

Signed at New York city, in the county of New York and State of New York, this 14th day of May, 1915.
